UNITED STATES PATENT OFFICE

133,670

DESIGN FOR AN AIRPLANE

Richard E. Metz, Lancaster, Pa.

Application March 10, 1942, Serial No. 106,141

Term of patent 7 years

To all whom it may concern:

Be it known that I, Richard E. Metz, a citizen of the United States, residing at Lancaster, in the county of Lancaster and State of Pennsylvania, have invented a new, original, and ornamental Design for an Airplane, of which the following is a specification, reference being had to the accompanying drawings, forming part thereof.

Figure 1 is a side elevational view of an airplane showing my new design.

Figure 2 is a top plan view.

Figure 3 is a front elevational view.

Figure 4 is a view similar to Figure 1, but showing the landing gears in operative position.

Figure 5 is a bottom plan view.

Figure 6 is a front elevational view showing the landing gears in operative position, and

Figure 7 is a rear elevational view.

I claim:

The ornamental design for an airplane, as shown and described.

RICHARD E. METZ.
